UNITED STATES PATENT OFFICE

HUGO R. SWANSON, OF BROOKLYN, NEW YORK, ASSIGNOR TO TRIANGLE KAPOK MACHINE CORPORATION, OF NEW YORK, N. Y., A CORPORATION OF DELAWARE

FIBER-TREATING DEVICE

Application filed March 27, 1928. Serial No. 265,103.

This invention relates in general to an improvement in devices for treating various fibers such as cotton, linters, kapok, felt fibers and the like.

5 One of the objects of this invention is the provision of means in the closed air circuit in devices of this type whereby the amount of air in the system may be changed during transient periods without interfering with 10 the normal operation of the apparatus.

These and other objects as will appear from the following disclosure are secured by means of this invention.

This invention resides substantially in the 15 combination, construction, arrangement and relative location of parts all as will be more fully described below.

Referring to the drawings,

Figure 1 is a longitudinal cross-sectional view 20 through the device of this invention showing the relative arrangement of the parts.

Figure 2 is a cross-sectional view taken on the line 2—2 of Figure 1,

25 Figure 3 is an end elevational view of the cone shaped member employed in this arrangement.

Figure 4 is a side elevational view of the 30 apparatus showing the device of this invention associated therewith.

In the treatment of fibers in their preparation for use in mattresses, cushions and the like, it is necessary to break up the fibers from a matted, compact form to a loose, fluffy condition and, at the same time, to remove therefrom all dust and foreign materials such as, for instance, seeds in the case of those fibers which contain them. One form of apparatus for carrying out these operations is disclosed

40 in my co-pending application Serial No. 235,767, filed November 26, 1927. The device of this invention relates to an improvement for use in an apparatus of this type in which during the transient periods while the blower 45 speed is changing the volume of air flowing through the conduit system may be varied as desired without interrupting the smooth flow of fiber laden air.

Referring to the drawings for a better understanding 50 of the invention there is shown

in Figure 4 a general assemblage of instruments comprising an aeration tank 10, having the inlet conduit 9 and the outlet conduit 1. The inlet conduit 1 extends into an enlarged cylindrical member 3 and is centered with respect thereto and partially supported by means of an annular screen 2 which completely encircles it as is clear from Figures 1 and 2. Attached to the cylindrical member 3 is a converging section 4 which joins with the cylindrical conduit 7 leading to the intake side of the blower 8. The delivery end of the blower is connected to the conduit 9. Mounted within the cylindrical member 3 and spaced therefrom is a conical member 4 which has its apex end projecting a short distance into the conduit 1. The conical member 5 is supported at a number of points by means of pins 6 attached to the cylindrical member 3 and spacing it therefrom.

The operation of the device is such that whenever the blower speed is varied so that the rate of travel of the air flowing through the conduit system changes, the quantity of air in the system may change by an influx or efflux of fresh air through the screen member 2. If a provision of this nature is not made, the fiber laden air due to its inertia piles up on one side or the other of the blower interrupting the smooth flow thereof during transient periods. In the case of influx the fresh incoming air contacts with and mingles with the air coming from the conduit 1 within the annular space formed by the wall or chamber 3 and the conical member 5. As a result the fresh air is mixed with and evenly distributed to the air already in the system without interrupting the operation thereof and without disturbing its proper operating conditions.

It is, of course, apparent that some changes 90 in the details of construction and relative arrangement of parts will readily occur to those skilled in the art and I do not, therefore, desire to be restricted to the form of the invention used for illustrating the principles 95 thereof, but rather to the scope of the invention as defined below.

What I seek to secure by United States Letters Patent is:

1. In a machine for treating fibers, the 100

combination with an aeration tank and a closed circulatory system having a blower therein, of means in said circulatory system for automatically introducing fresh air into the system during periods of blower speed change without an interruption of the operation thereof.

5 2. In an apparatus for treating fibers and the like, the combination with an aeration tank and a closed circulatory system communicating therewith and having means for creating a current of air therein, of means for automatically introducing fresh air into the system in response to variations in the 10 velocity of the air moving through the system.

15 3. In a device of the type described, the combination of a chamber, a screen forming one wall of the chamber, a conduit extending therein through said screen, and means in the chamber for deflecting the flow of air, as it leaves said conduit to enter the chamber, towards the walls thereof.

20 4. In a device of the type described, the combination comprising a cylindrical chamber extending into a conduit, another conduit extending into the other end of the chamber, a screen encircling said second conduit and forming a wall for the chamber, and conical 25 means supported within the chamber and away from the walls thereof for changing the path of flow of a gas in flowing from said second conduit.

30 5. In a device of the type described, the combination comprising a cylindrical chamber extending into a conduit, another conduit extending into the other end of the chamber, a screen encircling said second conduit and forming a wall for the chamber, and a conical member mounted within said chamber and 35 having its apex extending a short distance into said second conduit.

40 6. In a device of the type described, the combination of a first conduit having an enlarged portion, a second conduit extending into the enlarged portion and spaced from the walls thereof, a perforated annular ring encircling said second conduit and forming a wall for the open end of the enlarged portion of said first conduit, and a conical member supported within the enlarged end and having its apex projecting a short distance into the second conduit.

45 In testimony whereof I have hereunto set my hand this 22nd day of March, A. D. 1928.

HUGO R. SWANSON.
